UNITED STATES PATENT OFFICE.

CLEON TONDEUR, OF ITHACA, NEW YORK.

OIL-BURNER.

SPECIFICATION forming part of Letters Patent No. 278,374, dated May 29, 1883.

Application filed February 23, 1883. (No model.)

To all whom it may concern:

Be it known that I, CLEON-TONDEUR, a citizen of the United States, residing at Ithaca, Tompkins county, New York, have invented 5 an Improved Oil-Burner, especially adapted to use in glass-furnaces, of which the following is a specification, reference being had to the accompanying drawings.

My object is to take either crude oil or kerosene, or other burning-oil, and by faucets regulate its flow out of barrels or other oil-holders, interpose safety strainers or filters, and regulate the flow of the oil to the furnace, and at or near the furnace place further means of 15 regulating and facilitating the burning, as will be apparent as I describe my invention.

Figure 1 is a side elevation, and Fig. 2 shows my burner in use in a flatting-furnace. Fig. 3 shows my tuyère or burner, with round or 20 square ends, and Fig. 4 shows a two-necked bottle—a substitute for the faucet and single-necked bottle of the other figures.

In the figures, *a* is the pipe, with faucet *b*, which conveys the oil from the barrel or other oil-holder, and by which the regulated flow of oil 25 is conveyed to the chamber *c*, which chamber has a removable cap, *d*, which can be taken off by hand, or may be blown off by any gas that flows backward through the apparatus. This 30 chamber has (shown by the part cut away three or more) any convenient number of diaphragms, which are perforated, and on which are placed any suitable filtering substances or articles 35 that may be dissolved and aid in producing heat, as rosin. These sieves are removable—the upper one the coarsest in its apertures, the middle one finer, and the lowest quite small in its openings; and this chamber is funnel-shaped at its lower part, and empties thereby 40 the oil into the pipe *e*, which is provided with an upper faucet, *f*, and a lower faucet, *h*. The pipe *e* continues downward, and is joined to the pipe *i* in one round yet divided pipe, which has the faucet *h*, with two separate internal 45 tubular cavities. The united pipes are made fast to the screw-joint of the glass bottle *g*. The pipe *e* goes to the bottom of the bottle. The pipe *i* terminates at the top of the bottle. By this it will be seen that when gas flows 50 backward through the pipe *i* the oil in the bottle is forced upward into the top of the pipe *e*,

which may be made large enough to hold all the oil in the pipe *i* and bottle *g* before it reaches the chamber *c*; and if the regurgitation is violent, the gas escapes through the chamber *c* and cover *d* to the air, if the pressure is not relieved by the height of the column in the pipes. The bottle also is of use to see the flow of oil as well as to collect impurities. This vessel may be made with two mouths, 60 and the pipe *e* go into one mouth and the pipe *i* go out of the other mouth, as shown in Fig. 4; but the pipe *i* curves upward, whence it curves downward, descending to the right-angled joint, by which it connects with the enlarged pipe or long conversion-chamber *k*, which chamber, at its left-hand end, has a capped closure, *j*, and at its right-hand end is fitted to the tuyère or burner-point *m*. A rod, *n*, passes through it for the purpose of cleaning it. The tuyère *m* is large at its left-hand end, and it tapers toward the right-hand end to a fine point or end, where there is a circular or a slotted aperture, opening into the flame-chamber *t* of the flatting-furnace. In the 75 right-hand end of the burner is a tapering plug, *r*, that fits the point on the inside of the burner, and closes, when desirable, the aperture *o*. This plug is fast to the cleaning-rod *n*, and the left-hand end of the plug is made 80 the size of the narrow part *k'* of the connection to the chamber *k*, and is used to clean that connection and chamber. The chamber is fitted with cotton, broken pumice-stone, wool, or any other material thought suitable to regulate 85 the flow of oil or the heat of the oil in the chamber.

The plug *r* may be hollow, as shown in Fig. 3, and the oil or vapor of oil escape through it into the flame-chamber *t*, Fig. 2. The tuyère or 90 burner reaches inside of the furnace-wall *s*, or as near the flame-chamber as the volatilization of the oil may require, since, with purified oils, it is desirable that the volatilization of the oils be complete on reaching the flame-chamber. With 95 the crude oils it is necessary that the cruder parts drip out of the aperture and fall into the basin-hollow of the flame-chamber, where their combustion is completed. The flame-chamber is separated from the wheel-chambers or "lier" 100 by the side wall, *u*, which rises a little way above the basin of the flame-chamber. The rest

- of the flattening-furnace is constructed as usual, as is partially indicated in Fig. 2. One, two, or any requisite number of tuyeres or burners, or duplications of the whole device, are used side by side, as may be desirable; or, as seen in Fig. 2, the central pipe-chamber, *k*, supplies one or more tuyeres on each side of itself by side pipes, and which tuyeres have cleaning-rods *n*, with screw-threads and packed joints *j*.
- 10 The plug *r* I also make of platinum or refractory clay, hollow, as has been said and shown, and fitting tightly into the inner sides of the tuyere, so that the volatilization of the oil shall be into a complete vapor, and escape, not about the plug *r*, but through it. The drip-oil, if there should be any, shall escape by apertures *o*⁴ *o*⁵ in the tuyeres *o*⁰ *o*⁰⁰ just below the plug, as when I use the plug for both oil and vapor; or, the plug being solid, I use it as a feed-plug, 15 by it opening or closing the tuyere, that feeding the flame-chamber faster or slower, as desirable, being regulated by a screw-thread cut on the rod *n*, which fits the burr-thread cut in the cap *j*. The tuyere is represented in the 20 drawings as circular, with circular or oval aperture; but it may be made flat and with several apertures, or otherwise shaped and varied.
- At *o*, Fig. 3, is seen the end of the plug *r*, with a circular space or opening in the 25 tuyere *m* about the plug. At *o*⁰ is seen a flat tuyere, with a long or slit aperture in the plug *r*, and at *o*⁰⁰ a solid plug, *r*, with a four-sided aperture about the plug. The plug in all cases is made as said above, adapted to the 30 neck *k'* and hence it will be seen that by unscrewing the cap *j* the rod *n* and plug *r* are easily withdrawn out of the chamber *k*, bringing with them cinders or other contents of the chamber *k*; and, by what has been said above, 35 it is not meant that there is any complex tuyere or complex plug. In all duplications of the apparatus the tuyere and the plug are each one and the same, the tuyere being unchanged in all except that the additional aperture *o*⁴ *o*⁵ is made or not, as is best; the plug is made either solid or hollow to adapt it to either crude or

pure oils, the crude oils requiring several vents of gas, as indicated above, while the pure oils escape by one vent or opening, *o*, made either about or in the plug, as has been said.

50

The advantages and uses of my invention are apparent.

In an oil-burning device adapted for use in glass-furnaces I claim—

1. A device having the combined parts *a*, 55 the oil-supply pipe, the vent and filtering-chamber *c*, the conveying-pipe *e*, glass receptacle *g*, the upward and downward reflexed pipe *i*, chamber *k*, and tuyere *m*, operating as set forth.

2. The filtering and equalizing chamber *c*, provided with sieves *c'*, *c''*, and *c'''*, and the gas-escape cover *d*, and interposed between the pipes *a* and *e*, in combination with the elongated and static-producing pipe *e*, where- 65 by resistance is made to reflex flows of oil and gas, and the escape of gas is provided for when reflex action is inevitable, as set forth.

3. The combination, with each other, of the three diverse and regulating chambers or vessels between the oil-supply *a* and the tuyere *m*—viz., the capped gas-escape reservoir or chamber *c*, the tight and transparent chamber or bottle *g*, and the elongated and heat-regulating chamber *k*—the same being made and 70 operating substantially as set forth.

4. The apertures made below and next to the mouth of the tuyere *m* and operating independently of the main tuyere-apertures, whereby the crude, heavy-oil portion of the partially-burned oil escapes upon the glass-furnace burning-floor *t*, as set forth.

5. A chamber, *k*, and angular tuyere *m*, with internal plug, *r*, on the rod *j*, having a neck, *k'*, interposed between the chamber and tuyere, 85 through which the plug *r* passes closely, as shown and described.

CLEON TONDEUR.
